(57) **CLAIM**

The ornamental design for a combined water chiller, water fountain, and bottle filling station, as shown.

DESCRIPTION

FIG. 1 is a front isometric view of a combined water chiller, water fountain, and bottle filling station, incorporating the design;

FIG. 2 is a rear isometric view thereof;

FIG. 3 is a top view thereof;

FIG. 4 is bottom view thereof;

FIG. 5 is a front view thereof;

FIG. 6 is a rear view thereof;

FIG. 7 is a side view thereof; and,

FIG. 8 is another side view thereof.

The broken lines depict portions of the combined water chiller, water fountain, and bottle filling station that form no part of the claimed design.
